DESIGN FOR A WALL BRACKET LAMP

Edward Kanter, Cleveland Heights, Ohio

Application March 29, 1934, Serial No. 51,241

Term of patent 7 years

To all whom it may concern:

Be it known that I, EDWARD KANTER, a citizen of the United States, residing at Cleveland Heights, in the county of Cuyahoga and State of Ohio, have invented a new, original, and ornamental Design for a Wall Bracket Lamp, of which the following is a specification, reference being had to the accompanying drawing, forming part thereof, wherein Fig. 1 is a perspective view; Fig.

2 is a view in side elevation; Fig. 3 is a view in front elevation; and Figs. 4 and 5 are sectional views on the lines 4—4 and 5—5 respectively, of Fig. 1, of my design for wall bracket lamp.

I claim:

The ornamental design for a wall bracket lamp substantially as shown.

EDWARD KANTER.
